(57) **CLAIM**

The ornamental design for a process cartridge for image forming apparatus, as shown and described.

DESCRIPTION

FIG. 1 is a front view of a first embodiment of a process cartridge for image forming apparatus showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view 1 thereof;

FIG. 8 is a perspective view 2 thereof;

FIG. 9 is an enlarged perspective view of the portion defined by the A-A line and the B-B line in FIG. 7;

FIG. 10 is a front view of a second embodiment of a process cartridge for image forming apparatus showing our new design;

FIG. 11 is a rear view thereof;

FIG. 12 is a top plan view thereof;

FIG. 13 is a bottom plan view thereof;

FIG. 14 is a left side view thereof;

FIG. 15 is a right side view thereof;

FIG. 16 is a perspective view 1 thereof;

FIG. 17 is a perspective view 2 thereof; and,

FIG. 18 is an enlarged perspective view of the portion defined by the A-A line and the B-B line in FIG. 16.

The dashed broken lines illustrate portions of the process cartridge for image forming apparatus that form no part of
